WAVE PROPAGATING ELECTRON
DISCHARGE DEVICE

Albert Walter Lines, Stratford-on-Avon, England, assignor, by mesne assignments, to English Electric Valve Company Limited, London, England, a corporation of England

Application September 27, 1948, Serial No. 51,439
In Great Britain October 6, 1947

7 Claims. (Cl. 315—4)

1

The present invention relates to wave-propagating structures such as waveguide, strip transmission line and like devices of the type in which the phase velocity of electromagnetic waves is less than the free-space velocity, so that, for example, coupling may be effected to a stream of electrons falling through a potential difference of some few thousand volts, or less.

A known arrangement employing such a structure comprises an evacuated envelope containing a wire helix arranged axially in a metal tube. Such a construction results in a reduced phase velocity, and coupling may be obtained to a stream of electrons from a suitable gun located at one end of the tube: the structure is excited at the gun end of the tube, and by virtue of the coupling of the electromagnetic wave with the electron stream, an amplified wave is available at the other end of the tube. The phase velocity may be of the order of one tenth free-space velocity, and electrons falling through a potential difference of about 2 kv. couple satisfactorily with the wave. When the device is employed as an amplifier in the 10 cm. band, a bandwidth of the order of 800 mc./s. between 3 db points may be realised. By introducing a suitable feedback coupling, the device may be made to serve as an oscillator.

In adapting an arrangement such as is described in the preceding paragraph for use at higher frequencies or for working at higher power levels, certain constructional and other difficulties are encountered, and the present invention has for one of its objects to provide a waveguide, strip transmission line or like device which is capable of employment at such higher frequencies or higher powers, but whose construction is relatively straightforward.

The invention is based on the fact that the phase velocity of a component of an electromagnetic wave in a waveguide or strip transmission line with a uniformly-corrugated wall or walls can be made less than free-space velocity. (A component of the electromagnetic wave is one of the Fourier space harmonics of the wave, sometimes called Hartree harmonics.) In general, however, it is found that the dispersion of such a guide or transmission line for the largest amplitude components of the wave is high; that is to say, within a given frequency band, the phase velocity of the largest amplitude components at low phase velocities varies continuously between wide limits. This feature of corrugated structures is also a feature of any guide or like structure so formed that it is effectively a series

5 of similar resonators arranged uniformly end to end with respect to one another, the uniformly-corrugated guide and strip transmission line being examples of this class.

10 The principal object of the invention is to provide a wave-propagating structure such that the dispersion of the structure to a large amplitude component of electromagnetic waves propagated therein is low. A large component in this context is one with which a substantial fraction of the total energy in the wave is associated, and a low dispersion exists when, over a substantial frequency band, the variation in phase velocity is small; for example, over a frequency band of 15 some 10% of the mid-frequency, the phase velocity may vary by no more than 1%.

20 According to the invention in one aspect there is provided an electromagnetic wave propagating structure adapted to support electromagnetic waves having a phase velocity less than the free-space velocity of propagation, and having a low dispersion to a large amplitude component of waves propagated therein over a substantial band of frequency, said structure having at least one 25 boundary consisting of a conducting surface formed with a series of repeated like groups of resonators, the smallest repeated pattern of such resonators forming a group which is delineated by a particular pattern of variation in at least 30 one of the factors, the natural frequency and the spacing, of the resonators forming the group.

35 In another aspect, the invention comprises an electrical transmission system comprising a source of energy to be propagated, an electromagnetic wave propagating structure coupled to said source so that in the operative condition there are propagated in said structure electromagnetic waves having a phase velocity less than the free-space velocity of propagation, and having a low dispersion to a large amplitude component of waves propagated therein over a substantial band of frequency, said structure having 40 at least one boundary consisting of a conducting surface formed with a series of repeated like groups of resonators, the smallest repeated pattern of such resonators forming a group which is delineated by a particular pattern of variation in at least one of the factors, the natural frequency and the spacing, of the resonators 45 forming the group, and an output circuit coupled to said structure to receive energy from said source.

50 In yet another aspect the invention resides in an electromagnetic wave propagating structure 55 adapted to support an electromagnetic wave

having a phase velocity less than the free-space velocity of propagation, said structure comprising a conductive boundary surface formed with a series of resonators such as slots or cavities distributed along its length said resonators being arranged in recurrent, like, regularly spaced groups of three, the resonators of a group comprising two resonators of like natural frequency, and one resonator of different natural frequency from the other two.

A further aspect of the invention contemplates an electromagnetic wave propagating structure adapted to support an electromagnetic wave having a phase velocity less than the free-space velocity of propagation, said structure comprising a conductive boundary surface formed with a series of resonators such as slots or cavities distributed along its length, the spacing between successive resonators being varied in cyclic manner.

Yet another aspect of the invention involves an electromagnetic wave propagating structure adapted to support an electromagnetic wave having a phase velocity less than the free-space velocity of propagation, said structure comprising a conductive boundary surface formed with a series of resonators such as slots or cavities distributed along its length, every n th space between adjacent resonators being made equal to one another, but different from the remaining spaces, which are themselves equal, n being greater than unity.

The nature of the invention will be more clearly understood from the following description, and explanation of the behaviour of periodic structures propagating electro-magnetic waves, given with reference to the accompanying drawings, in which:

Figs. 1 to 8 are explanatory diagrams whose significance will appear hereinafter.

Fig. 9 is a diagrammatic representation of an electronic device according to the invention suitable for use on an amplifier or oscillator.

Fig. 10 is an enlarged cross-section view of a part of the device in Fig. 9, and

Figures 11a-e are representations of further embodiments of my invention.

If for an unloaded transmission line, the operating frequency f is plotted against $1/\lambda_g$ where λ_g is the wavelength in the line, a straight line 1 Fig. 1 is produced. The slope of this line f/λ_g will represent the free-space velocity of propagation of electro-magnetic waves, usually termed c . The same characteristic plotted for a waveguide will be as shown in curve 2. The phase velocity of the wave for any given frequency will be represented by the slope of the line joining the equivalent point on the curve to the origin. It will be observed that a low-frequency cut-off exists and the curve tends towards the free-space characteristic as the frequency is raised. The characteristic of a uniformly-corrugated strip transmission line shown in Fig. 2 is indicated in curve 3 of Fig. 1, the phase velocity decreasing from about the free-space value C as the frequency is increased from zero; phase velocity of $\frac{1}{2}C$ may be reached, for example, at the point a . Consideration of the behaviour of the corrugated waveguide may be simplified if the scales of the curves of Fig. 1 are changed to the alternatives shown, and

$$\theta = \frac{2\pi d}{\lambda}$$

(which is proportional to f), where d is the spacing between adjacent corrugations, slots or res-

onators, and λ is the free-space wavelength, is plotted against

$$\phi = \frac{2\pi d}{\lambda_g}$$

where λ_g is the wavelength in the loaded guide.

The uniformly corrugated guide, such as the strip transmission line with equal resonators spaced at equal intervals along one wall, is equivalent to a line loaded with circuits having a series of resonant frequencies, and exhibits a series of pass and stop bounds. At low frequencies the loading is inductive, and the frequency spectrum curve is as shown at 3 in Fig. 1. A high frequency cut off occurs when $\lambda_g=2d$, a standing wave being produced with antinodes of the longitudinal electric field at the lumped reactances. The frequency at which this occurs is less than the lowest resonant frequency of the loading reactance. This first resonance occurs when the effective length L of the resonator is

$$\frac{\lambda}{4}$$

and the attenuation in the guide is then infinite. From the cut-off frequency to the frequency at which the resonator length L is

$$\frac{\lambda}{4}$$

the phase change along one section of the guide remains at the value π . At the resonant frequency the loading on the guide changes from inductive to capacitive, and the phase difference across a section changes by π . The phase change remains constant at zero until the next pass band is reached. At the beginning of the second pass band the loading is capacitive, and the frequency spectrum curve is indicated at 4, Fig. 1. When the effective length of the resonator becomes

$$\frac{\lambda}{2}$$

it is again resonant with a node of the longitudinal electric field at the mouth of the resonator and $\lambda_g=\lambda$. For a higher frequency the loading is inductive and a cut off occurs at a frequency approaching the value for which the resonator length is

$$\frac{3\lambda}{4}$$

The same cycle of events is repeated at all resonant lengths

$$\left(\frac{n\lambda}{2} + \frac{\lambda}{4} \right)$$

At frequencies for which the effective length of the resonator is

$$\frac{n\lambda}{2}$$

the loading changes from capacitive to inductive and $\lambda_g=\lambda$.

At frequencies such that

$$\theta = \frac{2\pi d}{\lambda} = n\pi$$

further cut off values, not indicated in Fig. 1 occur. The stop band associated with a cut off of this type is the same as the stop bands obtained with inductive or capacitive loading. No resonance occurs in the cavities, and the phase change across a section of the guide remains constant throughout the stop band. On both sides of the stop band the pass bands are either both

inductive or both capacitive. In the former case

5

$\theta = n\pi$ is a low frequency cut off for the pass band and in the latter it is a high frequency cut off.

For a transmission line the frequency spectrum curve is given by $\theta = \phi$ (or $\lambda = \lambda_g$). The phase velocity, and group velocity defined (in terms of free-space velocity) by

$$\frac{\theta}{\phi} \text{ and } \frac{d\theta}{d\phi}$$

are equal to unity and independent of frequency. The transmission line is thus non-dispersive. With the introduction of lumped impedances or resonators at regular intervals along the line, a structure is produced exhibiting the characteristics of a dispersive medium. Phase and group velocities are different and dependent on frequency, the medium becoming more dispersive for the resonator case with increase of the ratio

$$\frac{L}{d}$$

For the first pass band of the corrugated strip transmission line phase velocity decreases from free-space velocity more and more rapidly with increasing frequency; at the same group velocity decreases to zero at the cut off frequency, a standing wave being produced with adjacent resonators oscillating in antiphase ($\lambda_g = 2d$). The occurrence of this standing wave indicates that the illustration of frequency spectra given in Fig. 1 are incomplete. They show only a single phase velocity at $\lambda_g = 2d$, whereas two equal waves with opposite phase velocities are required to produce a standing wave. The waves produced by reflections at the cavities are not included in the illustration of frequency spectra. At the same time it is evident that for any value of θ (or frequency), ϕ is multi-valued, with values differing by 2π . The longitudinal component of electric field E_z of the wave, which must exist along the corrugated surface at any particular instant of time is illustrated in Fig. 3, and so far only the fundamental component of this wave, shown by the dotted line, has been considered. The other components or space harmonics, have values of ϕ differing by $2n\pi$, where $n = 0, \pm 1, \pm 2 \dots$, the complete spectrum being as illustrated in Fig. 4. Thus for any frequency (f) the wave propagated in the corrugated structure may be analysed into a series of space harmonics, $a, b, c, \dots$ Fig. 4.

The relative amplitudes of these space harmonics depend on the specific boundary conditions enforced by the corrugated structure, and the amplitudes of the harmonics decrease with distance from the corrugated surface, the field due to the higher harmonics being of secondary importance as the axis of the main guide is approached.

Curve 5 of Fig. 1 indicates the characteristics of a rectangular waveguide with one wall corrugated, a structure which may be obtained by fitting side plates to the corrugated strip transmission line. The frequency spectra for the rectangular guide may be obtained from the spectra for the corrugated strip by replacing

$$\theta = \frac{2\pi d}{\lambda} \text{ by } \theta = \frac{2\pi d}{\lambda_{gw}}$$

where λ_{gw} is the wave-length in the resonators. The further explanation and description which follows is based, for simplicity, upon the characteristics of the corrugated strip transmission line; but the reasoning is equally applicable to the case of corrugated rectangular or circular waveguides and co-axials.

6

In the simple structure of Fig. 2 a standing wave can be set up for any frequency by a suitable arrangement of generators at the two ends of the structure. Then for all wavelengths in the structure, except $\lambda_g = 2d$, the wave pattern can occupy an arbitrary position with respect to the structure. In the case of $\lambda_g = 2d$, for which a standing wave occurs whatever the method of excitation, the pattern is fixed relative to the structure. Antinodes occur at the cavities, and nodes at points between the cavities. If now every N th cavity is modified by, for example, increasing or decreasing the length; then standing waves with the same wavelength but different frequencies can be obtained. Thus a standing wave can occur either with nodes or antinodes at the modified cavities. Evidently, the frequency of the standing wave with nodes at the modified cavities will be independent of this modification. However, the frequency of the standing wave with antinodes at the modified cavities will be increased or decreased according to whether the cavity has been decreased or increased in length. Each of these standing wave patterns will be fixed relative to the structure of the guide, and will not depend on the method of excitation. They will occur when the phase difference between the modified cavities is $n\pi$, or the distance between the modified cavities is

$$\frac{n\lambda_g}{2}$$

the reflections from the groups of cavities (N cavities per group) adding in phase and producing a standing wave. The wavelength in the structure at which these waves will occur are given by

$$\frac{n\lambda_g}{2} = Nd$$

or

$$\lambda_g = 2Nd$$

n

where N is the number of cavities in a group.

d is the distance apart of the cavities; and $n = 1, 2, 3 \dots N$.

Although the above description deals with modifications of every N th resonator, the results may be generalised to a corrugated waveguide consisting of like groups of N resonators.

In the preferred arrangement for introducing the periodic structure into the corrugated waveguide, the slots or resonators are grouped in threes, one resonator in each group having its length increased or decreased to a value l as indicated in Fig. 5. The effect of the introduction of this periodicity into the corrugated structure is to cause the phase velocity of frequency characteristic to break up, the lowest frequency pass band of the smoothly corrugated structure now being replaced by three separate pass bands separated by stop bands.

It is evident that standing waves will occur in this structure for $\lambda_g = 6d, 3d$ and $2d$. In the case of both $\lambda_g = 6d$ and $3d$, two standing waves are possible having either nodes or antinodes at the modified resonators. The frequencies of the standing waves with nodes at the modified resonators will lie on the spectrum curve for the simple corrugated structure. The frequencies of the standing wave with antinodes at the modified resonators will be higher or lower than these depending on whether the modified resonators have been made shorter or longer than the others. Hence two types of spectra are possible

and these are illustrated in Figs. 6 and 7, for $l > L$ and $l < L$. The dotted lines in Figs. 6 or 7 indicate the spectrum curves for the simple corrugated structures with corrugations all of length L or l .

For a complete illustration of the frequency spectrum of the corrugated guide with the periodic structure, the higher order space harmonics should be included. The curves for the various harmonics are of the same form as for the fundamental illustrated in Fig. 6 or Fig. 7. For each value of θ space harmonics are given by values of ϕ differing by

$$\frac{2\pi}{3}$$

the curve of Fig. 6 or 7 being repeated every

$$\frac{2\pi}{3}$$

as illustrated in Fig. 8 which indicates the first few space harmonics in the first, second and third pass bands when the modified resonator length l is shorter than the unmodified length L . The repetition of the pattern occurs every 2π if the groups of three resonators are considered as a single composite resonator, and the value of d adjusted appropriately. For the spectrum to be complete the space harmonics travelling in the reverse direction would have to be shown, as would also the fundamentals and harmonics corresponding to the higher frequency pass bands. For the purposes of the invention, however, only the low order harmonics in the low frequency pass band will, in general, be of importance as the amplitudes of the higher order harmonics are small and also the amplitude of the fundamental component is considerably greater than the amplitudes of the harmonics.

Consideration of the characteristics illustrated in Fig. 8 or Fig. 6 or 7 will show that particular frequency ranges can be selected over which one of the fundamental or space harmonic components exhibits non-dispersive transmission. Since non-dispersive transmission corresponds to uniform phase, and group velocities defined respectively by the ratio θ/ϕ , and the slope of the characteristic $d\theta/d\phi$ respectively, the non-dispersive regions will be characterised by coincidence of the tangent to the θ/ϕ curve and line joining the origin to the point of contact of the tangent. In other words, a non-dispersive region is defined by a substantially straight portion of the θ/ϕ characteristic which, when produced, passes substantially through the origin.

Such a result may be obtained with the described arrangement employing groups of three slots or cavities, one in each group being detuned, by operating about the frequency corresponding to point a indicated in Fig. 8. In this frequency region, the phase velocity of the fundamental wave may have a velocity of, say, $\frac{1}{2} C$ over a band width equal to say, 10% of the operating frequency. Non-dispersive regions with other phase velocities may be achieved by utilizing one of the space harmonics. For example, the second space harmonic may provide a region of constant phase velocity at b , Fig. 8, the velocity being considerably lower than that obtaining at point a . As previously stated, however, the field strength provided by the second space harmonic wave will be smaller than that provided by the fundamental and for a given R. F. power may not be adequate to provide the required degree of coupling to an electron beam, which is the

primary application contemplated for the constant phase-velocity wave. Again, non-dispersive regions may be located in higher main pass bands of the device which are not indicated in Fig. 8.

5 A frequency spectrum similar to that obtained with the structure illustrated in Fig. 5 may be obtained with an arrangement comprising groups of three resonators in which all resonators of a group are of different lengths, or resonant frequencies. The form of the characteristic will lie between those obtained for the three slot structure when one slot is detuned above and below the other two slots of each group. An arrangement alternative to the employment of groups

10 of three equally spaced slots with the periodicity defined by modifications in the resonant frequencies of the slots is an arrangement of groups of three slots with irregular spacing. This arrangement produces the same type of θ/ϕ characteristic as is produced by the structure of Fig. 5, and so long as the periodicity of three remains, the narrow stop band with the first main pass band are equally spaced, but the spacing d is measured as one third the spacing between the 15 groups of three resonators.

Other groupings of the slots or resonators to provide the periodic structure are possible, and an arrangement embodying groups of two dissimilar slots may be employed, or similar slots 20 may be arranged with alternately different spacings between successive pairs of slots. With these structures based on a periodicity of 2, only one minor stop band is produced within each major pass band and, in general, a non-dispersive condition 25 will not be realised with the fundamental component of the wave. However, on the higher space harmonic waves the θ/ϕ characteristics will have suitably sloping portions to produce the required non-dispersive propagation. The phase 30 velocities will, however, be lower than the velocities which would be obtained by utilizing the fundamental component. Groupings of larger numbers than three resonators may also usefully be employed to obtain the desired result of non-dispersive transmission at a particular frequency and velocity, each group of resonators being delineated by a particular pattern of variation in the natural frequency and the spacing of 35 the resonators forming the group.

40 The constant phase velocity result may be obtained if the corrugated waveguide with periodic structure is made as a corrugated strip transmission line or surface or as a rectangular waveguide with one or two opposite walls corrugated to form slots or resonators. The structure may 45 also take the form of a co-axial line with the corrugation formed on the inner or outer conductor. A circular waveguide with the desired form of wall may also be employed, but in this case, the inner diameter of the waveguide (measured to the surface of the corrugations or slots) has of necessity to be made so large that the transmission properties approximate those of a corrugated strip surface.

50 The corrugated waveguide structures according to the invention have a considerable advantage over known forms of travelling wave devices with low phase velocity as the attenuation is considerably reduced.

55 The device according to the invention may be constructed in any of a wide variety of different ways, provided that the structure effectively comprises a periodic structure of groups of adjacent slots, corrugations or resonators as set

forth above. The most convenient form consists of a rectangular waveguide with one wall corrugated, and may conveniently be formed by joining together a series of rectangular sections of appropriate cross sectional dimensions. Other forms, such as the co-axial line or circular waveguide, may be conveniently formed as suitably turned surfaces.

The various groupings of resonators and spaces which may be used in carrying out the invention are typified by the examples illustrated in Fig. 11. In this drawing Fig. 11a shows a group which corresponds to that described above with reference to Fig. 5, more groups, however, being shown and the vertical chain dotted lines showing the sub-division into groups. In Fig. 11b three groups are shown of a series in which each group comprises three equal spaces separating three resonators each of a different natural frequency. In the form shown in Fig. 11c the resonators are all of the same natural frequency but every third space is shown enlarged. In Fig. 11d again all the resonators are of the same natural frequency but the spaces vary in cyclic manner in a periodicity of three, each successive space being different from its predecessor. In Fig. 11e groups of three resonators are shown in which the second space in the group is made larger than the other two and the third resonator in the group is of a different natural frequency from the other two. Obviously other combinations of the two expedients of varying the spaces and resonator natural frequency may be devised and periodicities of more than three may be employed.

The electron beam, with which the selected travelling wave in the corrugated waveguide is required to couple, to make effective use of the properties of the device in the apparatus with which the invention is primarily concerned, may be provided by any known or suitable means. In the case of the rectangular structures, the electron beam may conveniently be of strip cross-sectional form, while if the structure is formed as a corrugated co-axial line, then an electron beam of annular cross section may be employed. Suitable focusing and directing means may be provided as desired to maintain the form of the electron beam and its transverse position in the guide structure; for example, the waveguide structure may have an arcuate form, or may be constructed as a closed ring, in which case a steady magnetic field is set up, in known manner, to constrain the beam to follow the desired arcuate path. The electron beam may in some cases be focused by means of crossed magnetic and electric fields, as in a magnetron oscillator.

By way of example, one form of device according to the invention, which has the merit that it lends itself to simplicity in manufacture is diagrammatically illustrated in longitudinal and transverse section in Figs. 9 and 10 respectively. This device, comprises a rectangular wave guide, 11, one wall of which is provided with slots p , q , r , p^1 , q^1 , r^1 , etc., equally spaced along its length and arranged as a periodic series in groups of three. The slots p , p^1 , etc., and q , q^1 , etc., being of equal length, the slots r , r^1 , etc., being of a different length. It will be seen that the smallest repeated pattern of slots is, therefore, a group of three, two long and one short and the total length of the waveguide is such that a large number of cycles of this pattern is included.

At the left hand end of the guide is an electron gun 12, arranged in a glass envelope 17 sealed to

the end of the guide and adapted to produce a wide, thin beam of electrons of the general form indicated at 18 in Fig. 10 when fed with suitable potentials via terminals 13, 14, 15 and 16. The electron gun 12 and the guide structure form an enclosed space which is evacuated.

Coupling means, in the form of short lengths of waveguide, 20 and 21, sealed off by glass windows 22 and 23 and coupled through slot type 10 matching transformers 24 and 25 with the end resonators are provided for feeding R. F. energy into and extracting R. F. energy from the left hand and right hand ends of the waveguide structure respectively.

When the device is energised at the proper potentials, an electron stream will pass through the device at a velocity which may be arranged to approximate to the phase velocity of an R. F. wave launched in it by the input waveguide 20 15 at the left hand end.

The waveguide structure 11 is conveniently constructed of metallic stampings of any suitable non-magnetic material, the thicknesses of which are arranged to provide the desired slot apertures, or the appropriate spacings between the slots and are stamped out to sizes appropriate to "p" and "q" slots, "r" slots or spacings between slots. A stack of such stampings is assembled and bonded into a continuously conductive structure for which purpose the meeting surfaces of the stampings are silver plated or otherwise treated to ensure low resistance contact conditions between them.

It will be appreciated that the arrangement 35 illustrated is diagrammatic and may be modified considerably in practice. For example, the method of coupling to the waveguide 11 may be varied considerably according to the design adopted for the structure and may comprise coupling loops or probes associated either with appropriate resonators or with the waveguide itself.

One such structure which has been made was built up from cooper stampings 0.080 inch thick, silver plated on one side, the complete assembly 45 being held clamped tightly together during a baking process carried out at a temperature of about 800° C. in a nitrogen atmosphere for a time sufficient for the formation of copper-silver eutectic bonds between adjacent stampings. In this example the waveguide was 4.81 inches wide, the free-space depth of the guide was 0.67 inch, the depth of the "p" and "q" slots (from the smooth wall of the guide) was 2.6 50 inches; and the depth of the "r" slots (from the smooth wall of the guide) was 2.00 inches. The waveguide when complete was found to have a non-dispersive pass band at a phase velocity of approximately 0.85 c. from 12.75 cm. to 140 cm. 55 wavelength.

The particular application in which the device according to the invention finds useful employment is the realization of a broad-band amplifier or oscillator for centimetric and millimetric wavelengths. In such an amplifier a device such as that described above with reference to Figs. 9 and 10 is employed, and the electron stream is fired axially down the corrugated waveguide structure at such a velocity that coupling occurs with that wave component which, over the desired operating band has a substantially constant phase velocity; the guide structure being suitably energized with the frequency to be amplified. The electron stream then causes 60 this wave component to build up exponentially

as it travels through the guide structure, owing to an energy interchange between the electron stream and the field, and a considerable amplification of the wave is obtained. The amplified R. F. output is obtained by suitable coupling arrangements at the output end of the structure.

Such a device may also be employed as a radio frequency oscillator in the centimetric and millimetric bands. In such an oscillator an arrangement similar to that outlined above as an amplifier is provided with a feedback coupling between input and output. Such an oscillator will have the advantage that its frequency can be adjusted over the band of frequencies for which the phase velocity is constant simply by the inclusion in the feedback path of a phase shifting device, without the necessity of readjusting the electron velocity, since the phase velocity is constant over the band of frequencies over which the oscillator is to be used.

I claim:

1. An electromagnetic wave propagating structure adapted to support an electromagnetic wave having a phase velocity less than the free-space velocity of propagation, said structure comprising a conductive boundary surface formed with a series of resonators distributed along its length, the spacing between successive resonators being varied according to a cyclically repeated pattern including at least three resonators and three spaces between resonators in each cycle of the pattern.
2. An electromagnetic wave propagating structure as claimed in claim 1 constructed to support an electromagnetic wave having a phase velocity less than the free-space velocity of propagation, said structure comprising a conductive boundary surface formed with a series of resonators distributed along its length, every *n*th space between adjacent resonators being made equal to one another, but different from the remaining spaces, which are themselves equal, *n* being an integer greater than unity.
3. An electromagnetic wave propagating structure as set forth in claim 1 wherein every third resonator is of a different natural frequency from the natural frequency of the remaining resonators.
4. An electromagnetic wave propagating structure adapted to support an electromagnetic wave having a phase velocity less than the free-space velocity of propagation, said structure comprising a conductive boundary surface formed with a series of resonators distributed along its length said resonators being arranged in cyclically repeated, like, regularly spaced groups of three resonators and separating spaces between resonators, each resonator of a group being of a different natural frequency.
5. In a structure for propagating electromagnetic waves, a conductive boundary defining a

plurality of groups of resonators which are spaced along the boundary in the direction of propagation with one group of at least three resonators for each half wavelength of a wave to be propagated, each group being identical with the others and each group being characterized by a predetermined cyclic variation in resonator spacing, the spacing between adjacent resonators being defined by longitudinal portions of said conductive boundary substantially parallel to the axis of said structure, the spacing between certain adjacent resonators differing from the spacing between other adjacent resonators.

6. In a structure for propagating electromagnetic waves, a conductive boundary surface defining a plurality of resonators spaced along the boundary in the direction of propagation, said resonators being in groups of at least three with one group for each half wavelength of a propagated wave, all the groups being identical with a variation between resonators of a group, said variation being cyclically repeated in said groups, said variation comprising a difference in spacing of the resonators of a group.

7. In a broad band high gain amplifying system, a path for radio frequency signal energy comprising a signal input, a signal output and an amplifying chamber directly connecting said input and said output, electron gun means having accelerating means positioned to project an electron beam through said chamber, said chamber having resonant portions acting to retard the velocity of radio frequency signal energy along said beam so that the component of velocity of said signal along said beam is of the same order of magnitude as the velocity of said beam and amplification of said radio frequency signal is obtained over a broad band and is produced by a continuously interacting energy interchange between the energy of said beam and the radio frequency signal energy, said resonant portions being arranged in groups of at least three resonant portions spaced from each other, the spacing of selected resonant portions differing from the spacing of the others to form a cyclic pattern of variation in spacing, said chamber having a plurality of such groups.

ALBERT WALTER LINES.
